12 Claims. (Cl. 202—121)

This invention relates to an improved apparatus for heating carbonaceous materials under such temperatures and conditions as will yield the greatest amount of valuable materials or substances such as condensates, a considerable carbon residue, and certain gases;—and this under maximum thermal efficiency and minimum operating costs.

By carbonaceous materials we refer to such substances as coal, lignite, wood, oil shale, coal tar pitch, petroleum coke, pitch coke, and any other material that when heated yields certain of the substances or bodies just above mentioned.

By condensate we mean all the condensable volatile matter resulting from the distillation of the above named materials.

By gas we mean such substances as do not liquefy under normal conditions.

Following the history of the coal carbonizing art from the early beehive oven down to the present highly efficient verticals and by-product ovens, the trend has been towards greater heating surface per unit of charge. At present the by-product ovens with a charge capacity of 15 tons have extended their walls to approximately 38 ft. long by 12 ft. high by 20 in. between walls. The beehive oven with equal capacity was approximately 12 ft. in diameter by approximately 10 ft. to the crown. Thus the increased heating surface has been obtained at the expense of an increase in the size of the equipment.

More recently designers have been attempting to obtain large heating surfaces in smaller units by the use of rotaries, internal heating, etc. The one great objection to internal heating is the uncertainty of uniformly heating the entire mass of the charge. This nonuniformity is caused by the common law of flow through the paths of least resistance, thus causing the more porous parts of the charge to become overheated while the less porous portions of the charge are practically untreated. This is especially true in coking a mass of coal. In the gas producer design the porosity of the coking mass of coal is obtained by mechanical pokers, moving grates, etc. In the coal carbonizing retort where coke is one of the products this mechanical movement would be unsatisfactory due to the amount of breeze produced.

The underlying feature of our apparatus is to obtain uniform heating of the mass throughout and without disturbance of the charge. This is accomplished by providing means for forming within the mass predetermined channels through which the gases or vapors are drawn, the

channels in the aggregate creating and affording a large surface of contact for such gases or vapors and a uniform distribution of the same throughout the mass. This arrangement enables one to use a relatively small retort and to carry out the process continuously, intermittently, or in batch operations.

One form of apparatus whereby the method may be effected, and more particularly as a continuous operation, is depicted in the annexed drawings wherein:

Fig. 1 is a horizontal sectional plan taken on the line I—I of Fig. 3;

Fig. 1^a, a detail view of certain of the driving mechanisms employed to move or actuate the scraper head;

Fig. 2, a vertical transverse sectional view taken on the line II—II of Fig. 3 showing the companion retorts and associated combustion chambers, together with other portions of the apparatus;

Fig. 3, a vertical sectional view taken on the line III—III of Fig. 2;

Fig. 4, a vertical sectional view taken on the line IV—IV of Fig. 5;

Fig. 5, a similar view taken on the line V—V of Fig. 4;

Fig. 6, a vertical sectional view taken on the line VI—VI of Fig. 5 and showing, more particularly, the conveyor mechanism employed to discharge the treated material;

Fig. 7, a top plan view of one of the carriages employed to position a charge within the retort;

Fig. 8, a vertical sectional view similar to Fig. 3 but showing the parts on an enlarged scale and 35 the empty car, from which the charge has been removed, withdrawn from beneath the retort;

Fig. 9, a perspective view of the charge-supporting bars which are utilized in conjunction with the grate-like bottom for the cars employed 40 to introduce the charges into the apparatus;

Fig. 10, a perspective view of such grate-like bottom;

Fig. 11, an end elevation of several of the grate bars with the intermediate supporting bars shown 45 in position with reference thereto, the supporting bars being in cross section;

Fig. 12, a horizontal sectional view taken on the line XII—XII of Fig. 11 illustrating the formation of the forward ends of the grate bars and 50 the manner in which they are shaped;

Fig. 13, a perspective view showing several of the grate bars and the finger or supporting bars;

Fig. 14, a transverse vertical sectional view taken on the line XIV—XIV of Fig. 6;

Fig. 15, a perspective view of the shearing or removing head employed to remove the treated material from the upper surface of the charge; and

5 Fig. 16, a perspective view of one of the shearing teeth or blades of the scraper or cutter.

A means for forming the predetermined channels within the mass forms the subject matter of our copending application for patent filed 10 January 4th, 1930, Serial Number 418,612, to which reference is made. This method will be hereinafter referred to in order that the present invention may be clearly understood.

In the construction illustrated a dual arrangement of retorts is shown;—this for the purpose of economy and speed in operation. It will be evident, however, that but a single retort may be employed in effecting the method or a number greater than two may be utilized. Inasmuch as 20 both retorts and the associated parts are alike in construction and operation a description of one will be given and the same reference numerals with the exponent *a* will be applied to the corresponding parts of the other unit.

25 In the drawings 1 represents a retort, preferably rectangular in cross section, said retort at its upper end opening into an elongated extension 2 which (see more particularly Fig. 2) is common to both of the retorts 1 and 1^a.

30 Located directly above the retort is a combustion chamber 3 the portion whereof is defined by an arch 4 having openings extending therethrough for the passage of combustion gas or other heating medium. The lower ends of these 35 openings are so formed as to secure a substantially even distribution of heat over the entire upper surface of the charge within the retort. This is effected by forming the lower portion of one side wall of each opening with an inclined face 5 (see Fig. 4), such faces inclining outwardly to each side of the center of the arch. This permits the heat rays or flames to be reflected from the longer walls of the opening outwardly past the inclined faces and directly onto the charge over its entire extent as indicated by the dot and 40 dash line in Fig. 4.

45 As above indicated, the charges are formed in receptacles 6 carried by cars 6^b, which cars carry the charge into line with the retort. The receptacle 6 is of a size equal to that of the opening in the bottom of the retort and is provided with a false bottom or grate of the form best shown in Fig. 10. Said grate is composed of a series of bars 7 mounted upon a series of rods 50 8 with interposed spacers 9 (Figs. 11 and 12) located on the rods between each pair of bars.

55 After the bars and spacers are assembled upon the rods they are placed in a press and the parts welded so as to produce a firm structure.

60 The rods 8 are positioned in the lower portion of the bars 7 so that a space is left between the spacer members 9 and the upper faces of the bars 7 of a depth sufficient to receive a series of supporting or finger bars 10. These finger bars are of a height less than the distance between the upper face of the spacers and the upper edges of the bars 7;—this for a purpose which will shortly appear.

65 The outer end of each of the bars 7, at one end of the grate, is beveled or inclined, as at 70 11, throughout the major portion thereof from the bottom upwardly (Figs. 11 and 13).

70 Each of the finger bars 10 is beveled or pointed at its outer end, which end will, of course, strike 75 the beveled face 11 when the finger bars are

moved inwardly, as will presently appear, between the grate bars 7.

75 Bars 10 at the ends opposite the beveled ends are rigidly affixed or secured to a header 12 from which latter extends a piston rod 13 actuated through an hydraulic cylinder and piston mechanism indicated by 14 (Fig. 3). Any other form of operating mechanism for shifting the supporting or finger bars may be employed.

80 It is designed, as above indicated and as set forth in our copending applications filed January 4, 1930, Serial Number 418,612, and October 6, 1932, Serial Number 636,611, and also application 636,612, filed October 6, 1932, of which this case is a division, to produce in the charge of material 15 to be treated, say coal, a plurality of spaced channels extending from the upper to the lower face of the charge and filled with a material which permits the free passage of gases therethrough and which is inert to the gases and is infusible 20 at the carbonizing temperatures.

85 Where coal is being treated these channels may be produced from coke, resulting from the process, or any other suitable material. They may be formed in various ways. One way is to place 25 a series of paper tubes upon the grate then resting in the bottom of the receptacle 6 upon a flange 12' which extends entirely around the lower inside edge of the receptacle. The paper tubes, as 13' (Figs. 3 and 5), are filled with the 30 granular coke which spreads outwardly over the grate bars to each side of the bottom of the tube, the lower end of which is held off of the grates so as to permit this spreading action. The space around and about the tubes is then 35 filled with coal. The tubes may be left in place as they readily burn out and permit the shearing operation of the treated material from the upper surface of the charge, as will hereinafter appear.

40 The outspreading of the channeling material 40 at the lower end thereof insures the integrity of the passage of such portion when the finger supporting bars are introduced in between the bars 7, as will be hereinafter set forth, and the grate is allowed to move downwardly into the receptacle 6 from which it and the superimposed charge have been removed or forced outwardly into the retort. It is to be understood that any means for forming the separated channels 55 50 may be utilized. Preferably they will be produced by a plurality of spaced metal tubes into which the channel forming material is placed and about which the material to be treated is filled, the tubes being then withdrawn. This is set forth and claimed in our copending application filed October 6, 1932, Serial Number 636,611. 55

Initially the charged car is introduced from a trackway 15 (see Figs. 1, 3 and 8) past a door 16, which at such time is lowered. The door 16 works to normally close off the outer end of an elongated chamber 17 which, as will be seen upon reference to Figs. 3 and 8, extends beneath the retort 1 and slightly beyond the same in order to allow certain portions of the car frame to be housed therein and thus bring the charge-containing portion of the car directly under the retort.

60 As the car is moved into the structure beneath the retort a second door 18 is lowered (door 16 at such time being closed) and after the car is 70 positioned beneath the retort the door 18 is again closed. Any suitable means for effecting a tight joint between the doors 16 and 18 and their respective guideways may be employed.

65 Suitable means must, of course, be provided for 75

moving the car in both directions along the trackage.

Secured to each end of the car, in order that it may be used reversely, and extending outwardly therefrom, is a frame member 19, the under outer portion of which is formed with a pocket 20, open at its lower end to receive the upturned end 21 of an actuating rod 22. Said rod, as will be seen upon reference to Fig. 8, 10 rests upon guide rollers 23 and 24, the rod extending outwardly of the chamber 17 through a stuffing box 25. Any suitable means for actuating the rod may be utilized and in the instant case there has been shown an hydraulic cylinder 26.

15 When the car has been moved from the position shown in Fig. 8 to the position shown in Fig. 3 and Fig. 7, bumpers 27 secured to the frame member 19 will contact fixed abutments 28 secured to the frame-work of the structure. Preferably these parts will be provided with shims 29 and 30, respectively, so faced that when the car is moved into contact therewith the charge-carrying portion of the car or receptacle will be absolutely aligned with the lower portion of the retort. Any other suitable means for securing registry of the receptacle with the retort may be utilized. Located below the retort is a lift or ram, the body or head whereof is preferably composed of a series of crossed beams designated generally by 31 the lower members of which are secured to and supported by the upper end of a piston rod working in an hydraulic cylinder 33. Tracks 32 are secured to the upper face of the uppermost beams. Also secured to the upper beams and extending at right angles to the tracks 32 are inverted T-shaped structural elements or beams 56.

40 Said last named beams are of sectional form to admit of the placement and securement of the tracks 32 which when the lift or head is lowered align with the tracks 15 and form an extension thereof so that the car may be moved from the position shown in Fig. 5 to that in Fig. 3. By having the T-beams 56 inverted no coal siftings 45 may gather or lodge on the upper edges thereof, thereby ensuring contact between said edges and the grate when the head is raised.

45 As a consequence, the head may be lifted or moved through a fixed distance at each operation with the assurance that the grate will be aligned with the fingers or bars 10 prior to the inward movement of the latter.

The head and tracks 32 are of such dimensions that they may be moved upwardly through the 55 receptacle 6 and carry the charge supporting grate therewith, the latter of course likewise being of such dimensions that it will move freely through the receptacle or charge-containing portion of the car. The grate, however, is made of such size as to make a relatively close fit with the inner wall of the charge-receiving chamber 60 so that the material resting on the grate will not pass downwardly around the same.

When the car with its charge is moved from the 65 position shown in Fig. 8 to that of Fig. 3 the ram is elevated and carries the charge and the grate upwardly until the grate stands in alignment with the supporting fingers or bars 10 which at that time are retracted or in the position shown 70 in Fig. 3. The ends of these bars pass through guideways 34 formed in the fabricated members of the structure.

When the grate and fingers or bars are in alignment the ram 14 is actuated and the bars 75 are moved inwardly. The beveled ends of the

bars 10 contact the beveled faces 11 of the grate bars 7, hence they are guided inwardly between the bars 7 without any shock or obstruction. At the same time the beveled ends of the bars 10 tend to wedge out any tar or material which may be lodged between the bars 7, forcing it up or down as the case may be. Continued movement of the head or member 12 will cause the ends of bars 10 to enter openings 24a (Fig. 3) in the frame and be supported thereby, (see 10 Figs. 4 and 8).

Thus the grate is cleaned prior to its being lowered back into the charge holding chamber carried by the car upon a lowering of the head and rod. When such retraction takes place 15 the charge which was in the receptacle and elevated therefrom is held in its elevated position, as shown in Fig. 8, by bars 10. These bars remain in such position until another charge has been drawn beneath the same and moved upward- 20 ly into contact therewith by movement of the lifting head or ram. When the upper face of the second charge contacts the bars 10 the bars are withdrawn and the upward movement of the ram continued so that there will be present in 25 the retort, as shown in Fig. 5, two superposed charges. The rods 10 will then be forced inwardly to maintain the superposed charges in position and the ram and grate again lowered. If desired, a third charge may be introduced and 30 moved upwardly, depending upon the height of the retort 1. It is not necessary in carrying out the operation that the charges be superposed as a single charge may be acted upon.

35 Located below the retort, and surrounding the ram, but standing in spaced relation thereto, is a pocket-like structure denoted generally by 35. Connected thereto is an offtake or suction pipe 36 which leads to the usual gas scrubbing equipment. Hand holes 37 are provided for clean- 40 out purposes.

Extending along the bottom of each side of the chamber 2 and placed in the walls of the retort are structural elements which form a track 38 upon which rest flanged wheels 39 arranged in 45 pairs at opposite ends of a scraper or cutter 40. The bottom of each side of the scraper head is provided with a plurality of spaced teeth 41 ar- 50 ranged in horizontal alignment and so proportioned and positioned as to just clear the upper end of the walls of the retort as the scraper is traversed back and forth within the chamber 2.

The scraper or cutter is designed to be moved over the upper end of the retort to scrape or shear off the then protruding finished material and to 55 push it out into a trough 42. One means of driving this head is shown. It comprises two endless chains 43 and 44 secured to outwardly projecting members 40 at the lower portion of the scraper body and passing about sprocket wheels 45 and 46, respectively. These sprocket chains and wheels, as will be best seen upon reference to Fig. 6, are mounted in pockets formed in the wall of the retort and entrance of coke, coal, or other material undergoing treatment and being trans- 60 formed into the pockets is practically precluded by the construction described. The sprockets are mounted upon shafts 47 and 48 which have their bearings in suitable standards 49 and 50 (see Fig. 2) mounted in pockets formed as a part of the 65 housing of the structure. Motion is imparted to the shaft 47, and consequently to the chains, through suitable gearing, such for instance as is shown in Fig. 1a, through an electric motor au- 70 tomatically controlled. 75

The material which has been treated is scraped off into the trough 42 and where the dual arrangement of retorts is employed, as best indicated in Fig. 2, the member 40 will be moved back and forth, first scraping the finished portion of the charge in the retort 1^a and then the similar material from 1 into trough 42.

A conveyor belt 51 passes along through the trough 42 and removes the material placed therein, discharging it through an opening 52, the discharge of which is controlled by a pocketed wheel 53 (Fig. 3) to prevent the ingress of air. This belt may be continuously driven or periodically operated as may be found necessary or desirable. Other suitable means to the same end may be employed.

Preferably, toward the discharge end of the trough 42, a quenching spray pipe 54 will be placed within the trough.

While the construction of the apparatus has been specified somewhat in detail, it is to be understood that the invention, insofar as details are concerned, may be varied without departing from the scope and spirit of the appended claims. It is thought that the operation of the apparatus will be understood from what has gone before but a brief résumé will be given.

Assuming that the apparatus is empty, a receptacle upon a car will be charged as above described and then moved in past the doors 16 and 18 successively. When it is positioned by contact between the bumper elements upon the car body and the fixed abutments 28 the ram will be raised, carrying the tracks 32 upwardly against the grate, thereby forcing the grate and the charge resting thereon upwardly into the retort until the grate comes into alignment with the fingers or bars 10 which are then moved inwardly to their full extent. The lifting head or ram is then lowered permitting the grate to move down into the receptacle 6, the charge remaining in the retort and being supported by the members 10. The car is then retracted and another charge brought in and the ram again elevated, the bars or fingers 10 being withdrawn during the upward movement of the second charge and upon completion of such upward movement again inserted.

The combustion gases are drawn downwardly through the channels 55 under a vacuum which will be varied according to the depth of the charge, as will be hereinafter referred to. The combustion gases will be drawn down through the checkerwork arch and by reason of the construction of such arch, as above set forth, will be evenly distributed over the entire exposed upper surface of the charge.

The combustion gases passing down through the predetermined spaced channels which are maintained throughout the charge will distribute the heat to the surrounding mass and gradually convert the same. At the same time the upper surface is exposed to the direct action of the gases and if coal be the material undergoing treatment it will be coked. When it is coked to a given depth the charge is raised and the coked mass is sheared off by causing the member 40 to be moved through the chamber 2 over the upper end of the retort, the then projecting coke being carried forwardly into the trough 42. This exposes a new surface of the material and this surface, together with the underlying layer is coked. The mass is then moved up and the operation of shearing repeated.

In practice the gas passing out of the apparatus has a temperature of approximately 80° C.

whereas with the ordinary coke oven the outgoing temperature has a range of approximately 1400° C. This is clear evidence that the heat is evenly distributed and absorbed through the mass in the present case, the heating taking place from the top downwardly. The capacity of the machine is primarily dependent upon the degree of suction set up within the apparatus.

The layout of the present construction affords wide variation of operation, which variation is also effected by the size and spacing of the pre-formed channels 55 as well as the depth of charge undergoing treatment.

The depth of the charge may vary from several inches to a greater or less number of feet and, as just mentioned, the size and spacing of the preformed channels may be varied. Successful absorption of the heat of the fluid heating medium may be readily effected with various depths and the nature of the product produced likewise varied and controlled; thus, if one holds the temperature for a relatively long period of time a harder and denser coke is produced than would be the case if the temperature were maintained for a relatively shorter period. We can completely carbonize a six inch body of coal within thirty minutes from a cold start, in which event it is necessary to replace the depth of charge every thirty minutes. The coke thus produced would be light and fluffy, similar to wood charcoal. On the other hand, it takes several hours to carbonize a body of coal say four feet deep. The upper six inches of such a four foot charge would be at a carbonizing temperature for several hours, resulting in the production of a hard dense coke.

In each case of operation it is possible to satisfactorily proportion the spacers and operating rate so that the operating temperatures of the fluid heating medium and the exhaust gases would be identical. Therefore, the height of the body of coal is only dependent upon the grade of coke desired. Naturally, it requires considerably more power input to the exhauster to draw the gases through a four foot bed of coal than in the case of a six inch bed. Furthermore, in changing from the thin to a thick bed, it is necessary to change the center distance of the channels. With a thin bed, say six inches, the channels will be relatively close, say approximately four inches from center to center, thus giving the depth of coal approximately two inches between the spacers for the heat to penetrate by conduction.

With a bed of four feet, the spacers would be from eight to ten inches on centers, thus making a depth of coal between the spacers approximately six to eight inches.

In the first instance, in which we have a cycle of thirty minutes, to complete the operation it is essential to secure quick penetration; whereas in a charge of four feet in depth it is not necessary to penetrate the charge throughout in less than several hours. The penetration of the heat throughout the mass of coal is of course necessary to a uniform heating of the charge. Therefore, the factors of height of the charge, time of operation, and center distance of spacers may be varied to obtain different densities of coke products. It has been found in practice that we can vary the product from a light fluffy char very similar to wood charcoal, to a dense metallurgical coke. Along with this variation in coke product, we have not experienced any material variation in our tar yields; the reason being that no matter where in the body of coal the tar distillation is taking place, it will always run down the spacers.

and away from that zone of heat where it is released from the charge, toward the lower cooler portion. In other words, immediately any tar is released from the coke it drops down through the channels and is therefore not subjected to any higher temperature than that which obtained to release it. In other words, the tar is not cracked as it is in the ordinary by-product oven.

It will also be understood that the make gas 10 passing from the apparatus may be utilized and enriched if need be with any desired fuel for burning in the combustion chamber of the retort. In fact any suitable heating medium may be utilized dependent only on the material to be treated.

15 It is also possible to burn any of the above mentioned fuels in an oxidizing atmosphere so that part of the heat is generated by the partial burning out of the spacer material, as for instance coke when coal is undergoing treatment. Such 20 coke would, of course, be infusible and thus the channels would be maintained open for the passage of the gases therethrough.

The term "ram" as used in the claims is to be treated as the equivalent of the lifting mechanism 25 which will accomplish the purpose set forth in the foregoing description.

As above noted, the drawings illustrate a dual arrangement of retorts. It is to be understood, however, that a single retort may be employed or 30 two or more retorts employed with a scraper as 40 common to all of them.

What is claimed is:

1. In an apparatus for treating carbonizable material, the combination of a retort having its 35 lower end open; a chamber in communication with said end; an open top receptacle; a removable bottom for said receptacle, said bottom having openings therethrough; means for moving said receptacle into the chamber and beneath the 40 retort; means located below and in line with the lower open end of the retort for contacting the removable bottom of the receptacle and raising the same thereby moving it and a charge which may be resting thereon from the receptacle and into 45 the retort; means movable into the openings in the bottom for arresting the descent of the charge when the bottom is lowered away from the charge and back into the receptacle; means for introducing a gaseous heating medium into the retort 50 above the charge and into contact with the upper exposed surface thereof; and means for drawing the heating medium downwardly through the charge.

2. In an apparatus of the character described, 55 the combination of an open bottom retort; a plurality of bars located to one side of the retort adjacent the bottom thereof; means for projecting said bars inwardly across the lower end of the retort; a receptacle for the material to be 60 treated; a false bottom in said receptacle, said bottom being formed with spaces through which the bars may pass when the bottom is in alignment with said bars; and means for moving said false bottom and the charge out of the receptacle 65 into the retort.

3. In an apparatus of the character described, 70 the combination of a retort having an open bottom; a receptacle for a charge to be treated; a removable bottom mounted in said receptacle and upon which the charge normally rests, said bottom being formed primarily from a series of bars 75 standing in parallel spaced relation to each other; means for moving said bottom and the charge thereon from the receptacle into the retort; and a series of finger or supporting bars

movable longitudinally of and between the bars of the removable bottom when the latter is within the retort and serving to hold the charge within the retort upon removal of the removable bottom therefrom.

4. In an apparatus of the character described, the combination of an open bottom retort; a receptacle; a false bottom for the receptacle and upon which a charge of material to be treated may be placed, said false bottom comprising a series 10 of spaced bars each being beveled at one end of the bottom; means for moving the false bottom and the charge out of the receptacle and into the retort without internal disturbance or rearrangement of the component elements thereof; a 15 series of finger bars located in line with the lower portion of the retort, the free ends of said bars being pointed at least from the upper face downwardly; and means for moving said bars inwardly between the bars of the false bottom, whereby a 20 support for the charge is produced permitting the withdrawal of the false bottom without disturbance of the charge.

5. An apparatus as set forth in claim 4, wherein the upper surface of the supporting or finger bars 25 lies in a plane below that of the upper surface of the bars of the false bottom, whereby said finger bars may be moved inwardly without disturbance of a charge resting upon the false bottom.

6. In an apparatus of the character described, 30 the combination of a retort having an open bottom; a receptacle in which a charge to be treated is placed; a false bottom within said receptacle and upon which a charge may be placed, said bottom being formed from a plurality of spaced bars 35 standing in parallel relation, the ends of each of the bars at one side of the bottom being beveled in a vertical direction throughout the lower major portion thereof; means contacting the removable bottom and carrying the same upwardly, together with a charge which may be placed thereon through the receptacle and into the retort; a series of finger supporting bars located in line with the bottom of the retort, the outer ends of the bars being pointed from the upper and lower 45 faces thereof, and the upper faces of said bars lying in a plane below the upper surface of the false bottom when the latter is fully positioned within the retort; and means for moving said finger supporting bars inwardly between the bars of the false bottom, thereby forming a temporary support for a charge and permitting the withdrawal of the false bottom therefrom.

7. A structure as set forth in claim 6, wherein the supporting bars are secured to a header at 55 one end.

8. In an apparatus of the character described, the combination of a retort open at its lower end; a chamber extending beneath and outwardly to one side thereof; a door located at the outer portion of the chamber; a second door located inwardly of the first door and adjacent the lower end of the retort; means for actuating said doors; trackage extending through the chamber; a car; a receptacle carried by the car and having a false bottom; a ram in vertical alignment with the lower end of the retort and having a portion of the trackage thereon, said trackage and ram being of such dimensions as to pass freely upwardly through the receptacle; means for moving said 70 ram upwardly; and means operative to hold a charge within the retort after it has been pushed outwardly from the receptacle in which it has been previously placed by the ram and false bottom.

9. A structure as set forth in claim 8, wherein 75

means is provided for moving the car over the trackage, said means being operated from without the chamber.

10. In an apparatus of the character specified, the combination of a pair of vertically disposed retorts standing in spaced relation to each other; a trough located intermediate said retorts; a combustion chamber located above each retort; means for introducing a gaseous heating medium into said chamber; means for drawing the combustion gases down through the retorts and charges placed therein; means for moving the charges upwardly within each of the retorts to project the finished product above the upper ends of the retorts; and a shearing head movable across the upper ends of said retorts and acting to carry the material into the trough.

11. A structure as set forth in claim 10, wherein in a conveyer belt works in said trough and the trough is provided with an air sealed outlet.

12. In combination with a retort, a combustion chamber located above the same; and an arch defining the lower portion of the combustion chamber and the upper portion of the retort, said arch having a plurality of openings extending therethrough from the retort to the combustion chamber with the lower portion of each of the walls defining such openings having an inclined face, such faces inclining outwardly to each side of the center of the arch. 5 10

Certificate of Correction

Patent No. 2,029,763.

February 4, 1936.

IRA H. DERBY ET AL.

It is hereby certified that errors appear in the printed specification of the above numbered patent requiring correction as follows: Page 3, second column, line 9, for "24^a" read 34^a; page 5, second column, line 14, claim 4, before "internal" insert *substantial*; and that the said Letters Patent should be read with these corrections therein that the same may conform to the record of the case in the Patent Office.

Signed and sealed this 25th day of February, A. D. 1936.
